UNITED STATES PATENT OFFICE.

STEWART CHARLES PAGET, OF WALLINGFORD, ENGLAND.

INTERNAL-COMBUSTION ENGINE.

1,272,305.

Specification of Letters Patent.

Patented July 9, 1918.

Application filed September 5, 1914. Serial No. 860,443.

To all whom it may concern:

Be it known that I, STEWART CHARLES PAGET, a subject of the King of Great Britain, and a resident of Ewelme, Wallingford, 5 Berkshire, England, have invented new and useful Improvements in Internal-Combustion Engines, of which the following is the specification.

This invention relates to internal combustion engines.

The object of my invention is to provide such a construction and arrangement of engine as will better maintain the working pressure on the piston during the working 10 stroke, and to better control the production of such pressure in accordance with the work required of the engine.

According to my invention I provide means for exploding the combustible gases 15 in a separate or secondary cylinder adjacent the working cylinder, to which secondary cylinder, the mixture is compressed and delivered by a pump or the like, and in which 20 second cylinder the charge is exploded, the gases being delivered to the working cylinder through a controlling valve.

The invention also comprehends means whereby the products of combustion ignited in the secondary or firing cylinder are placed 25 in communication with the working cylinder by suitable controlled valves actuated through the medium of an auxiliary motor, whereby the charges are transferred to the power cylinder to effect the operation of the 30 engine.

In order that the products of combustion 35 may be delivered to the working cylinder, a piston is arranged within the firing cylinder and adapted to be forced downwardly after 40 each explosion by means of the auxiliary power motor actuating a cam shaft engaging piston rods carried by each of the pistons so that after an explosion has taken place in the firing chamber, the piston therein is 45 forced downwardly through the medium of the cam shaft, thus delivering the exploded gases contained in the firing chamber rapidly into the working cylinder, it being apparent that a spring or other suitable means 50 may be employed for returning the piston to its normal position.

The valves for controlling the admission of the fuel charge to the firing cylinder, as well as the valve for controlling the communication between the firing cylinder and

power cylinder are operated by the auxiliary motor at preferably a much higher speed than and independently of the crank shaft of the engine, the auxiliary motor is not illustrated in the drawing, but it will be appreciated that any suitable type of power means may be used. By this construction, a number of charges may be led to the firing chamber exploded therein and transferred to the power cylinder during a working 60 stroke of the piston contained therein, to accord with the demand made upon the engine.

The return stroke of the piston drives the products of combustion out of the exhaust 65 port in the usual manner.

And in order that my invention may be more completely understood, reference should be made to the appended sheets of drawings which illustrate one example of 70 my invention.

Figure 1 shows in longitudinal section two cylinders of an internal combustion engine constructed and arranged according to my invention.

Fig. 2 is a section on the line X X of Fig. 1.

Fig. 3 is a transverse section on the line Z Z of Fig. 1.

A, A, are the working cylinders within 85 which the pistons B, B, reciprocate, said pistons having connecting rods C, C, connected to the crank shaft D in the usual manner.

Mounted within the cylinder head A¹ of the cylinder A, is a secondary or igniting cylinder E adapted to reciprocate within which is a plunger or piston E¹, provided with a tappet or piston rod E² having at its upper end a roller E³. The roller E³ is adapted to engage a cam K formed upon the shaft L in such manner that the plunger or piston E¹ will be depressed in order to scavenge the cylinder E of products of combustion. The piston E¹ is returned to its normal position by a spring E⁴. The cylinder E is adapted to be put into communication with the working cylinder A at the required time by the piston valve F.

Formed parallel to the cylinder E is the pump cylinder G provided with the plunger or piston G¹ adapted to be reciprocated by the connecting rod G² from the crank pin L¹ formed in the overhead shaft L.

A non-return valve H is placed at the lower end of the cylinder G and below which

valve is the transverse passage H^1 (see Fig. 3) to the inlet valve S of the engine, the said valve being operated from the cam shaft S^1 , in the usual manner.

5 The cylinder G is also provided with a delivery valve I of the piston type adapted to communicate with the said secondary cylinder E at the required time.

The two piston valves F and I are operated from eccentrics F^2 I^2 (see Fig. 2) mounted upon the lay shaft M , which shaft is connected to the overhead shaft L , by means of a chain N and chain wheels M^1 , L^2 , secured to the shaft M and L respectively, and runs at the same speed thereto.

The lay shaft M for operating the valves and the overhead shaft L are driven by suitable means, from an independent prime mover (not shown).

10 The cycle of operations is as follows:—On the opening of the inlet valve S , which takes place just prior to the working piston reaching its "in" dead center, mixture is drawn from the carbureter (not shown) by the piston G^1 through the passage H^1 , and the non-return valve H into the cylinder G where it is compressed by the return of the piston G^1 through the valve I into the secondary cylinder E . Immediately before the closing 15 of the delivery valve I , the valve F opens and the mixture being ignited by means of the spark plug E^5 , expands into the working cylinder A , forcing the piston B downward.

The cam K now depresses the tappet E^2 , 20 and the piston E^1 , scavenges the ignited charge from the cylinder E . When the valve F closes, the cycle in the cylinders E^1 , G , recommences and is repeated a number of times during the down stroke of the piston, a fresh expanding charge being admitted 25 to the combustion space of the working cylinder on each cycle.

Just prior to the piston B reaching the end of its stroke, the exhaust valve P opens, 30 and the products of combustion are scavenged out of the exhaust port P^1 by the return of the piston.

It will be obvious that although one igniting cylinder for each working cylinder is 35 described a multiplicity of such cylinders may be employed if desired.

The small cylinder E in which the explosions take place and in which the gases are generated under pressure and stored for a 40 short interval of time, being driven by a separate and independent prime mover may be driven at the desired speed in order to provide the necessary power in the working cylinder A . For example, in one working stroke of the working piston B , there may be three or four deliveries of combustion gases from the auxiliary cylinder E to one working stroke of the working piston, so that an increased power may be given the 45 working piston when it is desired to run this

engine at a lower speed and higher pressure. Or one such delivery only per working stroke may be made to give a smaller power.

Alternatively one such delivery might be made for four or more strokes of the power 70 piston, that is to say, one, or more than one stroke may be an idle stroke controlled in accord with the speed of the auxiliary prime mover. In this manner the working stroke might be cut out for one, two, or three revolutions when no power was required from the engine.

75 It will be understood that any prime mover may be used to operate the auxiliary pistons and valves, and such prime mover 80 may be an electric motor operated by or from energy provided by the power engine, as shown diagrammatically in Fig. 2 wherein the numeral 1 designates an electric motor of any conventional type driving a suitable belt 2 operating shaft M and controlling the sliding valves F .

85 What I do claim as my invention and desire to secure by Letters Patent is:—

1. An internal combustion engine, the combination with a cylinder having a piston therein, a secondary cylinder in communication with the cylinder, means for controlling the communication, means for introducing and exploding a series of fuel charges 90 in the secondary cylinder during a downward stroke of the power piston, and a scavenging piston arranged within the secondary cylinder for forcing the gases undergoing combustion from the secondary cylinder into the power cylinder after each explosion.

100 2. In an internal combustion engine, the combination with a plurality of cylinders having pistons therein, of a secondary cylinder for each cylinder in communication therewith, a valve for controlling the communication means for introducing fuel into the secondary cylinder and exploding the same therein, and a reciprocating scavenging piston arranged in the secondary cylinder 105 for forcing the gases undergoing combustion into the power cylinder.

110 3. In an internal combustion engine, the combination with a cylinder having a piston therein, a secondary cylinder in communication with the cylinder, a valve for controlling the communication means for feeding fuel and exploding the same in the secondary cylinder, a drive shaft overlying the secondary cylinder, and a piston arranged in the secondary cylinder and actuated by said drive shaft for delivering the gases undergoing combustion in the secondary cylinder to the power cylinder.

115 4. In an internal combustion engine, the combination with a plurality of cylinders having pistons therein, a secondary cylinder for each cylinder and in communication therewith, a valve for controlling the commu- 120 125 130

- nication means for introducing fuel into the secondary cylinder and exploding the same therein, an auxiliary motor, a shaft actuated by said motor, and a scavenging piston arranged in each secondary cylinder adapted to be reciprocated by the power shaft for forcing the gases undergoing combustion after each explosion from the secondary cylinder to the power cylinder.
5. In an internal combustion engine, the combination with a plurality of cylinders having pistons therein, of a secondary cylinder overlying each cylinder in communication therewith, and a fuel feed for each secondary cylinder, a sliding piston valve controlling said fuel feed, a sliding piston valve controlling the communication between the secondary cylinder and power cylinder, an auxiliary motor, and means connecting said auxiliary motor with said sliding valves whereby a series of charges may be delivered to the secondary cylinder and exploded therein during a single downward stroke of the piston in the power cylinder to accord with the demand upon the engine.
10. 5. In an internal combustion engine, the combination with a power cylinder and a piston, of a secondary cylinder and piston driven and controlled by an independent motor, said secondary cylinder being adapted to receive the fuel mixture and explode the same within the cylinder, the charges of gases undergoing combustion being transferred to the power cylinder as frequently as may be required in accordance with the demand upon the engine.
15. 6. In an internal combustion engine, the combination with a power cylinder and a piston, a secondary cylinder and piston driven and controlled by an independent motor, said secondary cylinder being adapted to receive the fuel mixture and explode the same within the cylinder, the charges of gases undergoing combustion being transferred to the power cylinder as frequently as may be required in accordance with the demand upon the engine.
20. 7. In an internal combustion engine, the combination with a power cylinder and a piston, a secondary cylinder and piston driven and controlled by an independent motor, said secondary cylinder being adapted to receive the fuel mixture and explode the same within the cylinder, the charges of gases undergoing combustion being transferred to the power cylinder as frequently as may be required in accordance with the demand upon the engine.
25. 8. In an internal combustion engine, the combination with a power cylinder and a piston, a secondary cylinder and piston driven and controlled by an independent motor, said secondary cylinder being adapted to receive the fuel mixture and explode the same within the cylinder, the charges of gases undergoing combustion being transferred to the power cylinder as frequently as may be required in accordance with the demand upon the engine, and means for controlling the transfer of gases while undergoing combustion from the secondary cylinder to the working cylinder.
